8 Claims. (Cl. 175—77)

This invention relates generally to a device for obtaining a sample from the wall of a cavity located below ground level, and more particularly to a device for recovering a core sample from the side wall of a drill hole.

In those areas of activity which involve explorations below the surface of the earth, there is great need for a simple, inexpensive method for obtaining true samples of the underground formations and recovering portions of their contained fluids. Such samples are directly useful to aid in the evaluation of the geological, mineralogical and physical properties and characteristics of the strata of interest. Such samples are particularly valuable in activities such as oil well drilling, since they may be analyzed to obtain information relating to the presence or absence of oil content, fluid storage and flow capacities, distribution of contained fluids, fluid flow characteristics, and the like of the strata penetrated.

The ever-increasing search for new oil and gas deposits in the United States has led to the drilling of holes at exceptionally great depths, for example 26,000 feet and more. The cost of sufficiently extensive coring during the drilling of very deep wells to be certain that no hydrocarbon productive zone is overlooked is excessive in many instances. Also, the likelihood of encountering difficulties during coring in long sections of open or uncased hole is great in some wells. Therefore, an instrument which permits recovery of a continuous sample from a pre-selected interval of drilled hole is of great value.

The technology of well drilling has advanced to the stage where the direction of the drill hole can be controlled, and the hole may be deviated in a predetermined direction if, by so doing, the chances of drilling into an oil or gas reservoir are increased. Samples of the sidewall of the drill hole, where the directional orientation of the core is established with the sidewall coring tool and the continuous core sample provides information relating to the dip of the strata, are invaluable in determining the directional trend of the strata sampled.

In those instances where a reservoir of oil or gas has been encountered, it is necessary to make a preliminary evaluation of the productive capacity in order to justify completion of the well. Also, there are many ways of completing wells into these reservoirs to recover the hydrocarbon deposits. For example, the hydrocarbon reservoir may extend hundreds of feet in depth, and one major problem lies in determining the vertical interval or intervals through which the casing should be perforated to provide maximum recovery at desired flow rates. Continuous samples of the profile of the formation are very important to such a determination.

The real merit of core or formation sampling is that an actual sample of the solid formation with the fluids contained in it is obtained. Usually, the most important information desired from the samples involves porosity, permeability, water content, and hydrocarbon saturation. Also, direct information relating to fluid flow characteristics, physical, chemical, electrical and acoustic properties, and the like, are valuable information which can be obtained only from actual samples of the formation.

Porosity is a measure of the fluid-carrying or storage capacity of the formation. Permeability indicates whether the formation fluids will be able to flow at rates

2

sufficiently fast to permit economical production of the hydrocarbon fluid contained in the formation.

It is most important to obtain the formation sample in the state in which it existed in the strata below the surface of the earth. Clearly, some of the determinations discussed above, which depend upon the physical structure of the core sample, will be inaccurate if the core sample itself is mishandled, such as by crushing or compaction.

For many of the studies for which formation samples are utilized, it is very helpful to obtain continuous samples from a relatively long distance along the formation profile. In other words, ideally, a formation sample would provide information from which the natural state of several feet of a formation profile could be reconstructed.

Formation samples obtained by conventional methods of sampling the wall of a drilled hole heretofore in use were less than ideal. One of the most widely used sidewall core sampling methods involves a device which inherently crushes or compacts part of the core sample. Such deviation from the natural structural state of the sample thus detracts from the accuracy of the information which is obtained by analysis. Likewise, there is not presently available any method of obtaining a substantial continuous length of sample from the walls of a drilled hole which would provide important data about the continuity of the profile of a particular formation.

Accordingly, it is an object of the present invention to provide an apparatus for obtaining a sample from the wall of a cavity below the surface of the earth which truly reflects the conditions prevailing within the formation.

It is another object of this invention to provide an apparatus for obtaining a sample from the side wall of a drill hole which is truly representative of a substantial length of the formation profile.

It is another object of this invention to provide an apparatus which is suitable for cutting and recovering a sample from a formation located below ground level, which sample is in a state substantially unchanged from that in which it was present in the formation.

It is another object of the invention to provide an apparatus for obtaining a sample from the side wall of a drill hole wherein the orientation and inclination of the sample are known.

Briefly stated, the method of the present invention for obtaining a sample of the wall of a cavity below the surface of the earth comprises the steps of making two longitudinal cuts in the wall, the cuts being co-extensive and in a V configuration, thereby forming a sample in the shape of a triangular prism, and recovering the said sample.

One embodiment of the apparatus of the present invention comprises a housing, cutting means located in said housing and adapted for making a pair of longitudinally co-extensive cuts in a V configuration thereby forming a sample in the shape of a triangular prism, and means located within said housing for recovering said sample.

The invention will be more readily understood when described in conjunction with the drawings, in which:

FIGURE 13 is a schematic view of a hydraulic system suitable for operation of the embodiment depicted in the drawings.

With respect now to the drawings, and more particularly FIGURE 1, there is depicted one embodiment 10 of the apparatus of the present invention, hereinafter referred to as a sampling device. A housing 11 in the form of a steel cylinder approximately six inches in diameter and twenty feet long is utilized to contain all of the elements necessary to cut and recover a sample. The cutting means employed in the embodiment depicted involves the use of two cutting wheels 12 and 13 mounted as shown in FIGURE 11, for example. As will be described in detail below, cutting wheels 12 and 13 utilize diamonds or similar cutting elements in order to provide cutting surfaces. Sampling device 10 is lowered into drill hole 14, as shown in FIGURE 1, by means of a cable 15 attached to the upper end of housing 11. When sampling device 10 has reached the desired depth, it is anchored in position by means of shoes 16.

By signals from the ground level, cutting wheels 12 and 13 are caused to rotate, are moved transversely into engagement with the side wall of the drill hole, and then are moved longitudinally of the wall of the drill hole thereby cutting a sample in the shape of a triangular prism. FIGURE 3 depicts the cutting wheels during the step of cutting the sample.

When the cutting wheels 12 and 13 have reached the end of their longitudinal travel, they are moved transversely out of engagement with the side wall and into the general position as shown in FIGURE 4. The anchoring shoes 16 are then retracted and device 10 is hoisted to ground level.

As will be described in detail below, a sample recovery means is provided to collect a triangular-shaped sample which is cut from the side wall of the drill hole.

The embodiment depicted in the drawings will now be discussed in detail. It is to be appreciated that the various features and structure of the embodiment may be modified to meet the individual requirements of other applications of this invention.

The embodiment to be discussed concerns the cutting and recovery of a section of the side wall of a drill hole. It is assumed that the drill hole contains a drilling mud of the type conventionally employed in oil well drilling operations. Device 10 is lowered into hole 14 by means of cable 15 which contains a plurality of insulated electrical conductors. The conductors are not shown in the drawings since such a cable is conventional.

When the device 10 is being lowered in the drill hole, it is necessary that it be properly positioned with respect to the formation which is to be sampled. Such location may be readily accomplished by utilizing conventional well-logging methods. These may be the usual S.P. log or gamma ray log or others which are suitable. Thus for

example, S.P. electrodes (not shown) may be connected to the housing 11 and these electrodes may be connected to ground level using the electrical conductors forming part of cable 15. Thus an observer at ground level will receive a continuous log of the formation as the device 10 passes down through the drill hole 14. When the device 10 reaches the desired formation, the cable pay-out is stopped.

The next step is to immovably anchor device 10 within the drill hole 14. For this purpose, a plurality of shoes 16 are provided. In the embodiment shown in the drawings, two shoes are used, one at the bottom and one at the top. However, it is to be appreciated that two shoes could be used at the top, spaced apart at a slight angle, and two shoes could be similarly positioned at the bottom.

In their retracted position, shoes 16 are flush with the outer surface of housing 11. This is shown in FIGURE 1. At a signal from ground level, shoes 16 are forced outward of the housing 11 so that the opposite surfaces of housing 11 are forced against the wall of the drill hole 14.

FIGURE 6 depicts one of shoes 16 in detail. In this embodiment, shoe 16 is operated by hydraulic pressure. Plate 17 is fastened to the inside of housing 11. Pins 18 and 19 are fastened to bearing plate 20 of shoe 16. Pins 18 and 19 pass through holes (not shown) in plate 17 and are spring biased by means of compression springs 21 and 22. Piston rod 23 is connected to bearing plate 20 and to piston 23 through a hole in plate 17. Piston 23 is housed in hydraulic cylinder 24. Hydraulic fluid under pressure is supplied to cylinder 24, in a manner discussed below, and thus piston 23 is forced out of cylinder 24. In this manner bearing plate 20 makes contact with the side wall of drill hole 14. This contact, in turn, forces housing 11 against the opposite wall of drill hole 14. Thus, housing 11 becomes anchored or wedged within drill hole 14.

Although the depth at which device 10 is anchored is known, the orientation of device 10 within drill hole 14 and the inclination of device 10 are not known. Orientation here is intended to denote the location of the sample to be cut with respect to true or magnetic north. Since these indicia are very important factors in the analysis of the samples which are recovered, provision is made for obtaining information relative thereto. There are instruments presently available which embody photographic means, a compass mounted on gimbals, and a means for determining inclination involving the use of a steel ball rolling freely in a curved glass cup. Instruments of this type are available from the Eastman Oil Well Surveying Company and the Sperry-Sun Well Surveying Company and are described more completely in the Eastman Directional Drilling Instrumentation Manual and the Sperry-Sun Well Surveying Instruments and Services Manual, respectively.

Controls for an instrument of the type described above, shown in FIGURE 1 by reference numeral 90, for determining inclination and orientation are connected to ground level by means of the insulated electric conductors in cable 15. After the device 10 is anchored within the drill hole by means of shoes 16, the instrument described above is actuated, and a photograph or recording is taken which will show the orientation and inclination of the device 10 at the time. The sample which is obtained will then be analyzed and the data obtained may be studied in the light of information relating to the sample location within the drill hole.

The next step involves energizing the power means used to rotate cutting blades 12 and 13. Electric motor 25 is the power means used, and it is located as shown in FIGURE 1. It is tubular in shape and is suitable for submerged operation. Typically motor 25 is a three-phase, 440 volt, 3 horsepower motor which is approximately four inches in diameter and three feet long.

Motor 25 is connected to gear box 27 by means of

adapter 39. The design of gear box 27 is shown in FIGURE 12. The shaft 26 of motor 25 is connected to input shaft 28 of gear box 27. Shaft 28 is connected to beveled gear 29 which in turn is meshed with beveled gear 30. Gear 30 is connected to cutting wheel 12 through shaft 34. Also connected to shaft 34 is beveled gear 31 which is meshed with beveled gear 32. Beveled gear 32 is connected to cutting wheel 13 through shaft 33. Gears 31 and 32 are of equal diameter and have equal numbers of teeth, and therefore cutting wheels 12 and 13 rotate at the same speed. The directions of rotation of the various parts of gear box 27 are shown by the arrows in FIGURE 12. The r.p.m. of motor 25 and the gear ratios of gear box 27 are chosen so that the cutting wheels 12 and 13 rotate at approximately 1800 r.p.m.

As stated above, the motor 25 is energized from ground level and this in turn causes cutting wheels 12 and 13 to rotate. The next step is to cause movement of cutting wheels 12 and 13 into engagement with the side wall of the drill hole 14 and then longitudinally along the side wall thereby cutting a V-shaped section.

As shown in FIGURE 1, motor 25 is connected to piston rod 35. Piston rod 35 is pivotally connected to piston 36 by means of wrist pin 37. Piston 36 is disposed within hydraulic cylinder 38. When device 10 is made ready for use, cylinder 38 is filled with hydraulic fluid. Device 10 is provided with a hydraulic system depicted in FIGURE 13. Suffice it to say at this point, that cylinder 38 is connected by solenoid operated valves 79 and 81 to dump chamber 77 where the hydraulic fluid force from the cylinder 38 may be stored.

After motor 25 is energized from ground level, valves 79 and 81 in line 78 between cylinder 38 and dump chamber 77 of the hydraulic system are opened by remote operation from ground level. Since housing 11 is not sealed but has openings therein, the pressure within housing 11 is equal to that within the drill hole. The pressure within housing 11 is exerted on the exposed face of piston 36.

As indicated above, device 10 is being described in connection with its use in an oil well drill hole. There is drilling mud in the drill hole. Therefore at the depths usually encountered in oil well drilling, the pressure in the vicinity of device 10 will be somewhere within the range of five hundred to ten thousand pounds per square inch. Since electric motor 25 is connected to piston 36, and gear box 27 is connected to motor 25 through adapter 39, the entire assembly moves in response to the movement of piston 36.

The manner in which cutting wheels 12 and 13 move transversely into the formation and then longitudinally along the formation, thereby cutting a triangular-shaped section, will now be analyzed in detail. Shown in FIGURE 10 is bracket 40 which is connected to gear box 27. Extending out from the sides of bracket 40 are bearings 41 and 42. Secured to these bearings are guide pins 43 and 44.

Provided within the housing 11, and rigidly attached thereto, are guide bars 45 and 46. These guide bars 45 and 46 are identical in configuration and are identically located on opposite sides of housing 11. Guide bar 46 will be discussed in detail since it is shown in FIGURES 5 and 6. However, it is to be understood that the remarks concerning guide bar 46 apply equally well to guide bar 45.

Guide bar 46 is provided with a slot 48. Guide pin 44 rides within slot 48. This is best shown in FIGURE 7, for example. Also shown in FIGURE 7 is guide pin 43 which is located within slot 47 of guide bar 45. As described below, the guide bar and guide pin assemblies function as a cam and follower to control the movement of cutting wheels 12 and 13.

In FIGURE 5 cutting wheels 12 and 13 are shown in their retracted lower position. (See also FIGURE 7.) As seen in this figure, guide pin 44 is positioned at the

lowermost point of slot 48. With the upward movement of piston 36 within cylinder 38, cutting wheels 12 and 13 move upward. Since guide bars 45 and 46 are stationary within housing 11, guide pins 43 and 44 ride upward within slots 47 and 48, respectively.

For the first short portion of travel, slots 47 and 48 are substantially vertical. Thus during the time that guide pins 43 and 44 travel within the vertical portion of slots 47 and 48, cutting wheels 12 and 13 move only in a vertical direction and have no transverse movement. However, when guide pin 44 moves into the inclined portion 49 of slot 48, cutting wheels 12 and 13 move both upward and also transversely. In other words, cutting wheels 12 and 13 begin to move out of housing 11 and into engagement with the side wall of drill hole 14. Since piston 36 moves only in a straight line within cylinder 38, the horizontal movement of cutting wheels 12 and 13 necessitates the use of wrist pin 37 to pivotally connect piston rod 35 to piston 36.

As shown in FIGURE 8, a portion of housing 11 is cut away to provide clearance room for blades 12 and 13 to move out of housing 11 and into the formation. FIGURE 8 depicts slot 50 which serves this function. It is to be noted that slot 50 affords a direct connection between the interior portion of housing 11 and the drill hole, and this opening plus other openings permit equalization of pressure within and without housing 11.

After the short inclined portions, slots 47 and 48 are vertical for a substantial distance. Thus, cutting wheels 12 and 13 move longitudinally of the side wall. FIGURE 3 shows the cutting wheels 12 and 13 moving upward through the formation. In the embodiment depicted, the vertical portions of slots 47 and 48 extend for approximately five feet, thereby permitting the cutting of a side wall sample of this length. It is to be appreciated that the length of sample to be cut by device 10 is a matter of choice, and this may be increased or decreased as desired.

Slots 47 and 48 have inclined portions at the upper ends, thereby directing the saw blades 12 and 13 out of the formation and back into the housing 11. Cutting wheels 12 and 13 are then located in their upper retracted position. The retracted position is the same, whether upper or lower. The wheels 12 and 13 are schematically depicted in the upper retracted position in FIGURE 4.

The operation of the device 10 has been described above with reference to the method of cutting the sample out of the side wall of the drill hole 14. It remains to describe how the sample is recovered. A sample recovery assembly 85 depicted in FIGURES 5 and 6, is employed for this purpose. It is to be appreciated that the recovery assembly 85 must follow or track cutting wheels 12 and 13 to insure recovery of the entire sample. To this end, recovery assembly 85 is attached to gear box 27 as described in detail below.

Lead section 51 of assembly 85 is hollow and is triangular in cross section at its upper end and is circular at its lower end. Lead section 51 has a bushing 52 connected as shown in FIGURES 5 and 10. Pin 53 is secured to bushing 52 and the ends of pin 53 are engaged in slots 55 and 56, respectively, which are located in bracket 40. Flat spring 57 is attached at its upper end to gear box 27. It is adapted to engage with bushing 52 as shown in FIGURES 5 and 10. Thus spring 57 is designed to urge bushing 52 in a direction toward the side wall being sampled. As shown in FIGURES 5 and 6, pin 53 is forced against the left hand wall of slot 55 as a result of the bias of spring 57. The circular end of section 51 is connected to upper portion 58 of a telescoping unit 60 by a pair of compression bands 88 and 89.

Assume the situation as depicted in FIGURE 5 of the drawings in which the cutting blades 12 and 13 are in their retracted lower position. After motor 25 has been energized and piston 36 commences its travel upward within cylinder 38, the movement of cutting wheels 12

and 13 is guided by slots 47 and 48 as discussed above. As cutting wheels 12 and 13 move into the formation and then commence their vertical upward travel, spring 57 forces section 51 to move into the kerf formed by blades 12 and 13. The reason that assembly 85 is slidably mounted to gear box 27 is that at the very beginning of the coring cycle insufficient material has been cut out of the formation to clear lead section 51 when it is in its normal position. Therefore, for the first few inches of travel, the formation will push lead section 51 toward the right against the force of spring 57. After the removal of the first portions of formation, lead section 51 will move back to the left under the urging of spring 57. Thus as can be seen in FIGURE 6, spring 57 has now pushed section 51 so that it is in perfect position to intercept the triangular-shaped sample as it is being cut.

With respect now to the telescoping unit 60 assembly 85, as stated above, section 51 is connected to unit 58. Unit 58 is telescopically connected to unit 59. Section 51 and units 58 and 59 are preferably made of heavy gauge metal. As seen in plan view in FIGURE 9, pins 61 and 62 are connected to unit 59. Pins 61 and 62 are engaged in slots 63 and 64 in brackets 65 and 66, respectively.

With reference now to FIGURE 5, unit 60 is depicted at a time when cutting wheels 12 and 13 are in the retracted lower position. In FIGURE 6, at a time when cutting wheels 12 and 13 are moving longitudinally along the side wall of drill hole 14, unit 60 has pivoted around pins 61 and 62 so that it is now substantially vertical. As cutting wheels 12 and 13 move upward, unit 58 slides out of unit 59. Unit 58 is provided with a lip 67 at the bottom thereof which engages collar 68 located at the top of unit 59. The engagement of lip 67 with collar 68 prevents unit 58 from being lifted out of unit 59. As cutting wheels 12 and 13 move upward along the side wall, to the midpoint of travel, units 58 and 59 are extended to their fully opened position. Slots 63 and 64 are provided to permit the entire telescoping unit 60 to move upward as wheels 12 and 13 continue their upward travel.

As stated above, it is very important to recover the sample so that the formation profile can be reconstructed at ground level. It is to be appreciated that the triangular-shaped section cut by wheels 12 and 13 does not stay in one piece. It is clear from the shape and location of section 51 that the sample must break off at intervals, and is in fact broken off by section 51. Of course, depending on the characteristics of the formation being sampled, there may not be sufficient cohesive strength in the sample being cut and it may break off due to vibration, for example. Since the total sample recovered may consist of a plurality of pieces, the method of collection must preserve the relationship of the pieces with reference to their respective locations in the formation. In the sample recovery assembly 85 depicted in the drawings, this is accomplished by collecting the pieces in an apparatus in which the pieces must line up, one on top of the other. In other words, the internal cross-sectional area of assembly 85 is chosen so that a new piece of sample being collected cannot slip past those already collected; the new piece is supported on those pieces already collected. Thus, when the telescoping assembly 60 is fully extended after the cutting operation is finished, the sample pieces are piled up, one on top of the other, within the assembly.

It is this feature of the apparatus of this invention which provides a relatively large sample of a formation profile having substantially the same structural integrity as when the sample was a part of the formation. The importance of this aspect of the invention cannot be overestimated.

It is to be appreciated that three or more sections could be used in telescoping unit 60 if desired. Also a collapsible unit made from metal mesh or canvas is suitable.

FIGURE 7 depicts cutting wheels 12 and 13 in their

lower retracted position. It can be seen that three cut-outs, 86, 69 and 70, are provided to house wheels 12 and 13. Of course, if wheels 12 and 13 were smaller in diameter, these cut-outs would not be needed. However, it is desirable to have as large a sample as possible, and by using wheels of the largest possible diameter, consistent with good design practice, the largest sample cross section is obtained. In the embodiment depicted, the blades are approximately six inches in diameter, substantially equal to the inside diameter of housing 11.

With respect now to cutting wheels 12 and 13, these are best shown in FIGURE 11. As seen, a plurality of cutting elements, such as diamonds, are embedded on the peripheries 71 and 72 of cutting wheels 12 and 13, and also on narrow rim portions 73 and 74 of both faces of the wheels. In addition, radial webs 75 and 76 are provided on both faces of the wheels 12 and 13 respectively, and these webs are also faced with cutting elements. The thickness of the peripheral portion of wheels 12 and 13 including the rim is greater than the thickness through the wheels measured from the surface of the web on one side to the surface of the web on the other side. This is to prevent binding of wheels 12 and 13 when cutting longitudinally of the formation.

At the beginning of the cutting process, wheels 12 and 13 move transversely into the side wall of the formation. During this movement, the cutting is being accomplished by the cutting elements embedded in the peripheral and rim portions and also by the elements embedded in the ribs on the outer surfaces of wheels 12 and 13. If there were no cutting elements embedded in the ribs of the outer surfaces of the wheels 12 and 13, the wheels would be unable to move into the formation.

As wheels 12 and 13 move longitudinally along the formation, the cutting is accomplished by the cutting elements on the rim and peripheral portions. As stated above, the thickness of the rim portion of wheels 12 and 13 is greater than the web cross-section. Thus, the kerf made by the rim portions is wider and the cutting elements on the ribs do not encounter the formation.

At the uppermost point of the longitudinal travel, wheels 12 and 13 begin to move transversely out of the formation. During this portion of the cutting operation, the cutting elements embedded on the inside faces of wheels 12 and 13 are utilized. This is necessary since the wheels must cut their way out of the formation.

Although the embodiment shown in the drawing utilizes cutting wheels as described herein, it is to be appreciated that other forms of cutters may be used. Thus for example, a rod or rods having cutting elements on the end and terminal portions thereof may be employed. Alternatively, instead of the use of two cutting wheels both mounted on the same gear box or motor, individually operable cutting wheels are also suitable. While in the illustrative device shown in the drawings an enclosed tubular housing is provided for supporting the work parts of the device in proper relative positions, it should be emphasized that many other different forms of support assembly may be substituted with equal efficacy.

FIGURE 13 is a schematic drawing of a typical hydraulic system suitable for use with the embodiment described in the above drawings. Depicted in FIGURE 13 are piston 36 and cylinder 38. Also shown is the hydraulic system of the shoes 16 showing pistons 23 and cylinders 24. Dump chamber 77 is connected to cylinder 38 through line 78 and remotely operated solenoid valves 79 and 81. Cylinders 24 are connected to cylinder 38 through lines 80, 82 and 87, remotely operable check valve 84 and remotely operated solenoid valve 81.

At the beginning of the operation, valves 79 and 81 are in the fully closed position. After device 10 has been lowered to the desired level, shoes 16 are activated in the following manner. Valve 81 is opened by signal from ground level. The hydrostatic pressure on the

lower face of piston 36 exerts a force tending to move piston 36 into cylinder 38. Since valve 81 is open, hydraulic fluid is displaced through check valve 84, lines 87, 80 and 82 into cylinders 24. The entrance of fluid into cylinders 24 pushes pistons 23 outward. Attached to pistons 23 are piston rods 83. The outward movement of piston rods 83 moves bearing plates 20 of shoes 16 into position.

When it is desired to commence cutting operations, remotely operated valve 79 is opened. Piston 36 then moves upward under the urging of the hydrostatic pressure and expels hydraulic fluid through valves 79 and 81 and line 78 into dump chamber 77. During this time, the pressure within cylinders 24 remains equal to the pressure within cylinder 38 and therefore bearing plates 20 of shoes 16 are maintained in their biased position against the side wall of the drill hole. Remotely operable check valves 84 serves to prevent a premature pressure drop within cylinders 24 by a flow of fluid out of cylinders 24 and back into the system.

When piston 36 reaches the end of its travel, the pressure will be equal throughout the system. Dump chamber 77 is made larger than the capacity of the balance of the hydraulic system, and the pressure therefore will decrease to a relatively low level within the system. At this point, check valve 84 is operated to permit back flow. Compression springs 21 and 22, shown in FIGURE 6 in conjunction with shoe 16, will force pistons 23 back into cylinders 24, and the fluid displaced will go through valves 84 and 79 into dump chamber 77. In this manner, housing 11 may be released when piston 36 has reached the end of its travel. Should it become necessary to pull the device out of the hole before the normal termination of the cycle, check valve 84 may be opened, valve 81 closed, and the pressure on shoes 16 released as described above.

The embodiment described above illustrates one apparatus useful in practicing the present invention. The apparatus shown in the drawings is to be considered illustrative of this aspect of the invention. Thus, for example, although the apparatus is described for use in an oil well drill hole, it is to be understood that apparatus of similar design can be used in any cavity of this nature located below the ground level. Changes in the design and structure of the apparatus described above may be made by one skilled in the art without departing from the spirit and scope of this invention.

What is claimed is:

1. In an apparatus which is to be lowered into a drill hole on a cable and includes a housing and means to receive a sample, means for cutting a sample from the side wall of a drill hole comprising a pair of cutters and means rotatably mounting said cutters within said housing in a V configuration with the apex directed outwardly of said housing, drive means within said housing to rotate said cutters, and means to move said cutters transversely into the formation beyond said side wall, then longitudinally of said drill hole and then transversely out of said formation, thereby severing from said formation a sample in the general shape of a triangular prism.

2. An apparatus for cutting and recovering a formation sample from the side wall of a drill hole comprising a support assembly, a pair of cutters rotatably mounted on said support assembly in a V configuration with the apex of said V directed outwardly of said assembly, drive means on said support assembly to rotate said cutters, means to move said cutters first transversely into the formation beyond said side wall, then longitudinally of said drill hole and then transversely out of said formation, thereby completely severing from said formation a sample in the general shape of a triangular prism, and collecting means associated with said support assembly for receiving said sample.

3. An apparatus for cutting and recovering a formation sample from the side wall of a drill hole comprising a support assembly having an opening in the wall thereof, a pair of cutters rotatably mounted on said support assembly in a V configuration with the apex of said V directed outwardly of said assembly, drive means on said support assembly to rotate said cutters, means to move said cutters through the opening in said support assembly, first transversely into the formation beyond said side wall, then longitudinally of said drill hole and then transversely out of said formation, thereby completely severing from said formation a sample in the general shape of a triangular prism, and collecting means associated with said support assembly to receive said sample as it is cut.

4. The apparatus of claim 3, in which said cutters are cutting wheels with cutting elements provided in the faces thereof for cutting during the transverse movements of said cutting wheels.

5. The apparatus of claim 3, in which said means to move said cutters includes cam surfaces mounted in said support assembly and cam follower means associated with said cutters.

6. The apparatus of claim 3, in which said collecting means has an input end with an opening therein for receiving said sample as it is cut, and means to move said input end in response to the movements of said cutters to follow generally the path of said cutting wheels.

7. The apparatus of claim 3, which includes means for sensing and indicating the orientation of said support assembly in said drill hole during cutting of said sample.

8. The apparatus of claim 3, in which said support assembly comprises a tubular housing.
